UNITED STATES PATENT OFFICE.

JOHN P. SCHOELERMAN, OF MONTE VISTA, COLORADO.

RAIL-JOINT.

1,244,378.

Specification of Letters Patent. Patented Oct. 23, 1917.

Application filed December 2, 1913. Serial No. 804,289.

To all whom it may concern:

Be it known that I, JOHN P. SCHOELERMAN, a citizen of the United States, residing at Monte Vista, in the county of Rio Grande and State of Colorado, have invented new and useful Improvements in Rail-Joints, of which the following is a specification.

The present invention relates to improvements in rail joints, the object of the invention being to provide the ends of two co-acting rails with interlocking means, whereby the said ends will be securely connected together against danger of lateral movement or downward flexure, and so provide a substantially continuous rail.

With the above recited objects in view, and others which will appear as the nature of the invention is more fully understood, the improvement consists in the construction, combination and arrangement of parts set forth in the following specification and falling within the scope of the appended claim.

In the drawings:

Figure 1 is a perspective view of a rail joint constructed in accordance with the present invention,

Fig. 2 is a central longitudinal sectional view of the same,

Fig. 3 is a transverse sectional view on the line 3—3 of Fig. 1,

Fig. 4 is a similar view on the line 4—4 of Fig. 1,

Fig. 5 is a perspective view of one of the rail ends, and

Fig. 6 is a similar view of the co-acting rail end.

The rails R—R' have their body portions constructed in the usual manner. The ends of the rails are, however, enlarged or thickened so that the webs upon one of the sides of each of the rails is disposed flush with the head of the said rail. Each of the enlarged ends is cut vertically and longitudinally to provide faces or walls which are flush with one of the faces of each of the webs of the rails. The straight vertical face of the enlargement of the rail R, indicated by the numeral 1, provides the head of said rail with an angular shoulder 7, the juncture of said shoulder with the said face 1 being rounded, as indicated by the numeral 8. The extension which is indicated by the numeral 2, is cut or otherwise

formed from the end of the base flange of the rail, so that the base flange is arranged approximately central of the end of the said extension 2 and the shoulder 7 provided in the head of the rail. The face 1, at a suitable distance beyond the terminal of the base flange is inclined outwardly, as at 3, to the end of the extension or projection 2. The end, however, terminates in an abrupt shoulder which is disposed at a right angle to the outer vertical face of the extension. The straight wall 1 from its outer end is formed with a centrally arranged channel 4, the said channel conforming to the shape of said wall 1, that is, the upper and lower walls of the channel are horizontally straight and the inner wall is vertically straight, but the said inner wall, adjacent the end of the extension, is beveled or inclined, as at 5, corresponding to the inclined face of the end of the rail, and the channel terminates in an inclined wall or shoulder 6. The vertical wall of the channel 4 is provided with a plurality of bolt receiving openings 9.

The inner straight wall or face of the enlargement of the rail end R' has its head terminating in a shoulder 10, the said shoulder being disposed a suitable distance at the rear of the terminal of the base flange 11, and the end of the rail is extended a suitable distance beyond the terminal of the base flange, the distance between the end 11 of the base flange and the end of the extension equaling the distance between the end of the base flange of the rail R and the shoulder 7 provided by the head of the said rail R. The inner face of the rail from its shoulder 10 is beveled or inclined outwardly, as indicated by the numeral 13, and is from thence continued longitudinally in a vertically straight plane, as indicated by the numeral 14. The inclined and longitudinally extending portions 13 and 14 have centrally and integrally formed thereon a longitudinally extending rib 15, the rib being shaped to be snugly received within the channel 4 of the rail R, and so the said rib, while presenting an outer longitudinally extending vertically straight face for a certain distance from the end of the rail extension has its inner portion inclined, as at 16, toward the web and the shoulder 10 of the rail R', this portion corresponding to the inclined portion 5 of the channel 4. The outer end 110

of the rib 15 is beveled, as at 17, in an opposite direction to the inclined or beveled terminal of the channel 4 of the rail R, and the inner face of the wall 14 has its extremity beveled or rounded, as at 18, to correspond with the beveled or rounded corner 8 provided at the juncture of the shoulder 7 and the inner face of the rail end R. The rib 15 is provided with a plurality of elongated slots 19 corresponding in number with the bolt openings 9 of the rail R, and adapted to register with the said openings. When the rails are assembled, suitable securing bolts 20 are passed through the registering openings and the said bolts are provided with retaining nuts 21.

From the above description, taken in connection with the drawings, it will be noted that I have provided a simple, strong and efficient joint for the meeting ends of railway rails, one wherein the tongue or rib not only engages within the channel of the co-acting rail, but in which the peculiar formation of the co-acting faces of the rail ends provide an effective lock between the said rail ends. It will be noted that when assembled, the portion of the rail ends projecting beyond the terminals of the base flanges rest upon the upper faces of the base flanges of the opposite rails; and that the joint effectively provides for the expansion and contraction of the rails, without subjecting the

ends of the rails to creeping by the wheels of the rolling stock passing thereover.

Having thus described the invention, what I claim as new is:

In combination, a pair of rail ends each having a base, a web and a head, the web of said rail ends being thickened and each provided with a projecting portion, the thickened portion of one rail end being entirely on one side of its web and that of the other rail end being on both sides of its web, said thickened portions being arranged in over-lapping relation and having opposing faces extending from the base to the upper surface of the head, and respectively provided with a longitudinal groove and a tongue to fit in said groove, the opposing ends of said tongue and groove being beveled, the projection of the first-named rail end being beveled at its outer end and the inner end of the doubly thickened portion of the other rail end being correspondingly beveled, and bolts extending through the over-lapping portions of the rail ends and securing them together.

In testimony whereof I affix my signature in presence of two witnesses.

JOHN P. SCHOELERMAN.

Witnesses:

JACOB F. SCHOELERMAN,
CHRISTIAN J. THOMSEN.
